US0D1076516S

(12) **United States Design Patent** (10) **Patent No.:** **US D1,076,516 S**
(45) **Date of Patent:** **** May 27, 2025**

(54) **CHASE**

(71) Applicant: **MILLERKNOLL, INC.**, Zeeland, MI (US)

(72) Inventors: **John Matthai**, Holland, MI (US); **Joel Ruiter**, Ada, MI (US)

(73) Assignee: **MILLERKNOLL, INC.**, Zeeland, MI (US)

(**) Term: **15 Years**

(21) Appl. No.: **29/755,528**

(22) Filed: **Oct. 21, 2020**

Related U.S. Application Data

(62) Division of application No. 29/710,203, filed on Oct. 21, 2019, now Pat. No. Des. 903,382, which is a division of application No. 29/648,707, filed on May 23, 2018, now Pat. No. Des. 868,509.

(57) **CLAIM**

The ornamental design for a chase as shown and described.

DESCRIPTION

FIG. 1 is a perspective view of a chase; FIG. 2 is a first side view thereof; FIG. 3 is a second side view thereof; FIG. 4 is a first end view thereof; FIG. 5 is a second end view thereof; FIG. 6 is a top view thereof; and, FIG. 7 is a bottom view thereof.

The evenly spaced broken lines depict portions of the article that form no part of the claimed design.

The chase is shown with a symbolic break in its length. The appearance of any portion of the article between the break lines forms no part of the claimed design.

1 Claim, 5 Drawing Sheets
